UNITED STATES PATENT OFFICE.

JOHN L. NILSON AND JOHN PRINCE, OF CHICAGO, ILLINOIS.

MULTIPLE-SPARK PLUG.

1,327,057.

Specification of Letters Patent.

Patented Jan. 6, 1920.

Application filed February 19, 1917. Serial No. 149,432.

To all whom it may concern:

Be it known that we, JOHN L. NILSON and JOHN PRINCE, citizens of the United States, residing in the city of Chicago, county of Cook, and State of Illinois, have invented certain new and useful Improvements in Multiple-Spark Plugs, of which the following is a specification.

Our invention relates to spark plugs for internal combustion engines, and has particular reference to constructions wherein several spark gaps are provided. In the present invention the two gaps are arranged at the inner, or explosion, end of the plug, and the object of the invention is to provide what may be termed the "stepping stone" electrode, with a minimum amount of metal, or heat-retaining material, and to provide a mounting of said electrode which is a safe-guard against breakage of the porcelain core or insulating material on which it is placed. With these objects in view the invention consists in the novel construction, combination and arrangement of parts, all as herein-after described in detail, illustrated in the accompanying drawing, and more particularly pointed out in the appended claims.

In the drawing—

Figure 1 is an elevation, partly in section, of a spark plug embodying our invention.

Fig. 2 is an enlarged bottom plan view of same.

In the several views 2 represents the porcelain core or insulation through which the center wire or electrode —3— passes. The core 2 is shown held in a usual cylindrical and threaded jacket or portion 4 with the aid of a bushing 5 and packing 6. The side electrode —7— is mounted in the usual place and in the usual manner, but is limited to a straight piece of wire instead of the usual elbow form with a leg directed toward the tip of the electrode 3. In the space between the wires 3 and 7 two spark gaps 8 and 9 are separated by a short section of wire, plug, or double-headed and pointed rivet 10 that is held in a bore 11 made at one side and at the tip of the porcelain core 2, as shown in the two views. The bore 11 may be made large enough to prevent crowding of its rivet or intermediate electrode when expanded by heat. This form and method of mounting of the intermediate electrode obviates retention in the intermediate electrode of sufficient heat to cause untimed, intermediate or accidental ignitions of the explosive

compound and effects a substantial saving in the amount of metal required for its construction. This single-point intermediate electrode may also be otherwise mounted and arranged without departing from the spirit of our invention.

Having thus described our invention, we claim as new and desire to secure by Letters Patent—

1. In a spark plug, the combination with its metallic jacket and an insulating core constructed and arranged with a spark gap between said core and jacket and a spark gap bore within said core but open to the exterior of the plug and to the gases to be ignited, of an electrode wire having its ignition end in said bore, and an intermediate electrode piercing the wall of said bore and providing an intensifying spark gap between said wire and said jacket, the latter serving as the "ground" electrode.

2. In a spark plug, the combination with a metallic shell or jacket, of an electrode wire having its ignition end spaced apart from the walls of said shell or jacket and exposed to the gases to be ignited exteriorly of said plug to provide a spark gap therebetween, a bored insulating core having a wall interposed between said ignition end and the wall of said shell or jacket, and an intermediate electrode, also exposed to the gases to be ignited, and having its ends at opposite sides of said wall.

3. In a spark plug, the combination with a longitudinally bored core having its bore open to the gases on the exterior of said plug and a metallic shell or jacket in which said core is held and from a portion of which it is spaced to provide a spark gap between said core and jacket, of an electrode wire having its ignition end spaced apart from said core to provide another spark gap within the core, and an intermediate electrode which bridges the spark gap spaces between said ignition end and jacket.

4. In a spark plug, the combination with an insulating core having an enlarged bore at its ignition end which is open to the exterior of said plug and provides a space, of a single binding-post electrode wire having a part in said space and spaced apart from the walls thereof, a metallic jacket for said core having a part thereof spaced apart from said core, and a rivet and the like electrode which pierces a wall of said core and provides two spark gaps between said core

and said jacket and said single binding-post electrode wire.

5. In a spark plug, the combination with a conducting jacket and an insulating core with a space therewithin that is open to the exterior of the plug, of an electrode spaced apart from the walls of said space, an electrode on said jacket also spaced apart from said walls, and an intermediate electrode

which passes through said walls to form an exposed spark in said space within the core and another spark on the exterior of said core.

In testimony whereof we have hereunto signed our names.

JOHN L. NILSON.
JOHN PRINCE.
